UNITED STATES PATENT OFFICE.

JOSEF FRANZ ZARUBA, OF HAMBURG, GERMANY.

GAS-FIRING.

SPECIFICATION forming part of Letters Patent No. 729,989, dated June 2, 1903.

Application filed July 8, 1901. Serial No. 67,417. (No model.)

To all whom it may concern:

Be it known that I, JOSEF FRANZ ZARUBA, a citizen of the German Empire, and a resident of Hamburg, Germany, have invented 5 certain new and useful Improvements in Gas-Firing, of which the following is a specification.

This invention relates to a method of firing in which hydrogen, water-vapor, and oxygen 10 or air are burned. These three gases are separately introduced into the fire-chamber, so that the water-vapor neutralizes the well-known injurious effect of the pointed-cone flame found in hydrogen firings. At the same 15 time the vapor is to prevent the explosion liable to occur with oxyhydrogen gas. The gas used is pure hydrogen, which receives the oxygen necessary for combustion either from the air or from a direct supply of oxygen 20 when the air is cut off. If desired, the oxygen may also be supplied in addition to an air-supply. In all cases, however, water-vapor under the lowest possible pressure is used, which is admitted simultaneously with the 25 oxygen in such a manner that the hydrogen and oxygen are only brought into contact with one another after they have been mixed with the water-vapor. This result is accomplished by arranging the steam-tube between the hydrogen-tube and the oxygen-tube.

The drawings represent three examples of an apparatus for carrying the invention into effect.

Figure 1 is a longitudinal section of one 35 form of the apparatus on line A B, Fig. 2; Fig. 2, a side elevation thereof; Fig. 3, a front elevation; Fig. 4, a longitudinal section of a modification on line C D, Fig. 5; Fig. 5, a longitudinal section on line E F, Fig. 4; Fig. 6, 40 a cross-section on line G H, Fig. 4; Fig. 7, a plan of a further modification; Fig. 8, a longitudinal section on line I K, Fig. 7, and Fig. 9 a cross-section on line L M, Fig. 7.

In Figs. 1 to 3 the apparatus comprises 45 three tubes *a*, *b*, and *c*, which are arranged close to one another and of which the outer tubes *a* and *c* serve for supplying, respectively, hydrogen and oxygen or air, while the central tube *b* serves for supplying the water-vapor. The ends of the three tubes *a*, *b*, and 50 *c* are united in a casing *d*, composed of two

parts which may be of equal size and are connected by screws *e* or in similar manner. At the ends the tubes *a* and *c* are provided with burners of steatite or other refractory material, which are slotted similar to gas-burners, so that the hydrogen and oxygen are spread fan-like. The steam-supply pipe *b* is also provided with a similarly-shaped nozzle.

In Figs. 4 to 6 each tube *a*, *b*, and *c* is inserted into a chamber *f* and is provided with a suitable number of branches *g*, *h*, and *i*, which are led outward through upwardly-extending apertures *k* of the chambers. The ends of the tubes may also be provided with 65 steatite burners or nozzles of refractory material. The chambers *f* are formed of refractory non-heat-conducting material, such as fire-brick, magnesite, Dinas brick, &c.

In Figs. 7 to 9 the pipes *a*, *b*, and *c* are not 70 led through the chambers *f*, as in Figs. 4 to 6; but the chambers are themselves used for conducting the gases which issue from the nozzle-like tapered openings *l* into the fire-chamber. The openings *l* converge upwardly 75 to form slits, so that the gases issuing therefrom are spread out fan-shaped.

In operating a boiler, furnace, stove, &c., according to my invention I proceed as follows: The tube *a* is first opened and the hydrogen gas is ignited in the known manner. The tube *b* is then opened, so that water-vapor is supplied to the hydrogen. Finally, the tube *c* is opened to carry oxygen to the combustion-chamber. Thus the hydrogen 85 and oxygen gases are diluted by the water-vapor before being allowed to combine. The supply of the gases as well as of the water-vapor is regulated by suitable cocks or valves arranged within the tubes *a*, *b*, and *c*. If 90 atmospheric air is admitted, only a very small quantity of oxygen is to be introduced, which may sometimes be omitted altogether. In order to avoid errors in manipulating the cocks, their handles may be so connected that 95 the oxygen-cock cannot be opened previous to the opening of the hydrogen-cock. It will be seen that the water-vapor flows for the entire length of the fire-chamber centrally between the hydrogen and the oxygen, which 100 likewise flow over the entire length of the fire-chamber. In this way a direct contact

of the pure hydrogen with the pure oxygen and a consequent formation of oxyhydrogen gas is avoided. The concentrated heat of the hydrogen-flame is reduced by the water-vapor, and in this way the heat is diffused through the entire fire-chamber.

As the new method of firing does not require any draft, chimney and blower are rendered unnecessary, while the formation of smoke and soot is avoided.

What I claim is—

1. A method of firing which consists in diluting hydrogen and oxygen gases with water-

vapor, and then causing the diluted gases to combine, substantially as specified.

2. A method of firing which consists in injecting into a fire-chamber hydrogen, oxygen, and water-vapor intermediate the hydrogen and oxygen, substantially as specified.

Signed by me at Hamburg this 21st day of June, 1901.

JOSEF FRANZ ZARUBA.
